Attorney

UNITED STATES PATENT OFFICE.

JOHN T. CLARK, OF PROVO, UTAH.

NECKTIE HOLDER.

Application filed December 27, 1921. Serial No. 524,840.

To all whom it may concern:

Be it known that I, JOHN T. CLARK, a citizen of the United States, residing at Provo, in the county of Utah and State of Utah, have invented certain new and useful Improvements in Necktie Holders, of which the following is a specification.

My invention relates to neck tie holders, and has for its object to provide a simple and economical device on which a neck tie of the four-in-hand type may be knotted and by which said tie may be fastened in place and adjusted in a turned down collar as the said collar is worn.

15 These objects I accomplish with the device illustrated in the accompanying drawings in which similar letters of reference indicate like parts throughout the several views, and as described in the specification forming a part of this application and pointed out in the appended claim.

In the drawings in which I have shown a substantial embodiment of my invention, Figure 1 is a plan view of the device. Figure 2 is a plan view of the device with a tie knotted thereon. Figure 3 is an edge view of the device, with the flexible cord removed.

20 In order to avoid knotting the tie in the collar each time it is worn I have invented a tie holder consisting of a piece of spring wire bent medially of its length to form an elongated or V-shaped loop with a portion A in the plane of the medial portions of the device and spaced apart to engage the shank of a collar button. The other or end portion of the said loop is bent forwardly and inclined downwardly to engage the end of the collar button and is extended beyond the 25 collar button to form the disengaging lug or loop B. A sheave loop C is formed in each of the free end portions of said wire and an eye loop D is provided on each end of the wire. Between the loops C and D on each 30 end portion of said wire a curve E is formed and the said curved portion E and the loops D are twisted or bent towards the rear in order that the plane of that portion is at

an angle to the general plane of the loops C and the button engaging portions of the 50 device. A flexible cord F is secured at its ends to the said eye loops D and passed through the said sheave loops C; if it is so desired a lighter cord F may be used and as shown in the drawings the cord is passed 55 through the eye loops D and two leads of cord are used with the knot G or other fastening means uniting the two ends of the cord between the sheave loops C. The tie is to be knotted on the reach of cord between 60 the said sheave loops C and in use is to hang over the button engaging portions A and B of the device.

The portions of each wing of the device from the loops C outwardly are inserted 65 under the lapels of the collar and the button engaging loop A is pushed upwardly, by placing the end of the thumb against the lower end of the loop B, until the device is in place on the button. The tension of the 70 wings of the device especially the curves E will draw the tie knot snugly within the end portions of the collar and when in use no portion of the device can be seen, while the tie is held in place similar to the same type 75 of ties wherein the knot is formed each time the tie is worn.

Having thus described my invention I desire to secure by Letters Patent and claim:

A neck tie holder comprising a piece of 80 spring wire having a button engaging loop medially therein and with the sides of said loop spaced apart to engage the shank of a collar button, the end portion of said loop extended and bent forwardly and inclined 85 downwardly, a side loop in each free end of said wire, an eye loop on each end of said wire, a curve formed in each end portion of said wire between each of said side loops and the respective eye loops, and a flexible 90 cord passed through each of said side loops and engaging the eye loops and on which a neck tie is to be knotted.

In testimony whereof I have affixed my signature.

JOHN T. CLARK.
